[57] CLAIM

The ornamental design for a recipe box, as shown and described.

DESCRIPTION

FIG. 1 is a front perspective view of a recipe box showing my new design with the lid in an open position; FIG. 2 is a front elevational view of the recipe box of FIG. 1;

FIG. 3 is a rear elevational view of the recipe box of FIG. 1;

FIG. 4 is a side elevational view thereof, the opposite side is a mirror image;

FIG. 5 is a top plan view of the recipe box of FIG. 1;

FIG. 6 is a bottom plan view of the recipe box of FIG. 1;

FIG. 7 is a front elevational view thereof in a closed position;

FIG. 8 is a rear elevational view of the recipe box of FIG. 7;

FIG. 9 is a side elevational view of the recipe box of FIG. 7, the other side view being the same;

FIG. 10 is a top plan view of the recipe box of FIG. 7; and,

FIG. 11 is a bottom plan view of the recipe box of FIG. 1.
